FLOOR FURNACE WITH REMOVABLE
HEATER UNIT

Carl B. Richardson, Norfolk, Va.

Application December 11, 1946, Serial No. 715,538

2 Claims. (Cl. 126—116)

1

This invention relates to a novel hot air furnace, more especially of the type commonly known as floor furnaces, adapted for installation immediately below a floor and having its discharge of heated air through said floor.

Such furnaces are customarily used in connection with homes, usually of moderate cost, having no basements or cellars, necessitating the provision of a well or pit below the ground floor in which the heating apparatus must be installed.

Although the equipments in vogue have been found quite efficient in operation, serious difficulties have been encountered where the apparatus is to be used in successive seasons, in keeping the same clean, free from rust and consequent impairment, and in the inaccessibility of the critical or main operating parts of the apparatus for necessary repair, in instances requiring the services of more than one repair man.

The invention has for an object, in the preferred embodiment of the invention, the provision of a floor furnace preferably of stainless steel or non-rusting material, substantially all operating portions of which are removable from the pit or well, upwardly through the floor where they are fully accessible for convenient cleaning, repair, etc. through the efforts of a single operator, if necessary, and permitting a simple, quick and easy reassembly in the pit or well when the parts have been treated as desired, preferably between successive winter seasons or, in fact, any time conditions so require.

Simplicity of construction and consequent inexpensiveness in manufacture, installation and repair are also underlying objects in the production of the said preferred embodiment of the invention.

A special formation of communication or connection between the exhaust flue of an outside casing and an inner flue from a heating chamber whereby the latter may be tilted and shifted laterally to permit the upward lift thereof through the top opening after the grills and their attached baffles have been removed;

A fire pot having means facilitating combustion of air and gas mixtures therein discharging into an upstanding chimney or flue for delivering the products of combustion into a surrounding heating chamber at a point substantially above an outlet to the inner flue from the heating case to the exhaust flue or chimney of the outside casing;

Means permitting detachment and vertical removal from the outer casing of either or both

2

the fire pot or heating chamber surrounding the same; and

Means permitting a removal by an upward lift of the fire pot and its parts, the heating chamber and its parts, and a base or platform for the heating chamber from the outer casing.

All of the foregoing, and other novel features of the preferred embodiment of the invention, will be more fully apparent and understood from 10 the detailed description, hereinafter contained, when read in connection with the accompanying drawings, forming part hereof, and wherein—

Figure 1 is a vertical sectional view of the furnace, the fire pot and the soot catch plate 15 forming a part thereof being shown in elevation.

Figure 2 is a vertical sectional view of the fire pot.

Figure 3 is a horizontal sectional view through 20 the apparatus taken on the line 3—3 of Figure 1 and looking downwardly or towards the bottom of the fire pot.

Figure 4 is a sectional view on the line 4—4 of Figure 1 looking downwardly.

Figure 5 is an enlarged vertical sectional view 25 of the meeting or nesting portions of the grill sections and immediately associated parts.

Figure 6 is a vertical sectional view of the outer or "cold" section of the associated grill alone, the inner or "hot" section being removed.

Referring more particularly to the drawings wherein the same reference numerals designate like parts in the several views 11 represents the floor of the room or house to be heated, said floor being adjacent to the surface of the ground 30 wherein a pit or well 12 is formed in keeping with known practices, the same being of any desired construction with its walls faced and protected, if desired, or bare where climatic and soil conditions justify, and 13 represents the bottom of the pit or well. This pit or well in itself constitutes no departure from customary practices, nor is it a characteristic feature of the instant invention.

A metallic outside casing 14 (preferably stain- 45 less or rustless steel, as is substantially all of the parts to be herein described)—conveniently of rectangular contour (Figure 3)—is formed in the well 12 and fitted between the top and bottom thereof as a matter of relatively permanent fixture in said well.

This outside casing rests in, or carries a pan 50 disposed at the bottom of the well to exclude, within reasonable height, water or other accumulations in the bottom of the well above the pan, as will be obvious. The corners of the outside

casing 14 are formed of upright angle bars 16, the flanges of which are of considerable width overlying correspondingly shaped corner braces 16a and spacers 17, to form vertical ways or grooves 18, for a purpose to be later pointed out, it being here noted that the uprights or angle bars 16 and spacers 17 extend well below the bottom platform or supporting member 19 for the fire pot 20' and associated mechanical structure thereabove.

Extending around the interior of the apparatus, so as to bridge the angle corners 16 and spacers 17, is an inverted U-shaped bar 20, a depending flange 21 of which is welded to the walls of the angle spacers 17, and another depending flange 22 of which terminating in a ledge 23, receives the supporting member or platform 19, the latter having a surrounding depending flange 24 adapted to bear on the underlying shelf 23 and detachably locked in position through the medium of connections approximately described as ball and socket fittings 25, formed by indentations and rounded projections as best seen in Figure 1. The metal and associated parts are such that an attachment or detachment of the platform with its support may be effected by tilting or swinging the base or platform 19 upwardly.

Surrounding the fire pot 20', and substantially enclosing the same, is a metal casing 26 forming with one wall 27 of a heating chamber 28, a chamber 29, into which ample outside air may be admitted through the openings in the angle corner members 16 and spacers 17, constituting the legs of the apparatus and supplied to the combustion areas of the fire pot through apertures 30, in the wall of the fire pot, and 31, in a contracted neck portion 32 thereof, to be later referred to. The casing 26 has flange portions 33 and 34 welded to the three adjoining walls, as 27 of the heating chamber 28, and a similar flange 34' welded to the fourth or remaining wall of the said heating chamber at the lower end thereof.

It will be appreciated that it is altogether desirable that as much heat as possible be conserved in the heating chamber 28, and to that end conduction of the heat from said chamber through the metal wall thereof to the metal supporting platform 19 and therebeyond is prevented, said chamber is insulated all around from said supporting platform by the interposition of non-conducting washers or strips 35 between the upper surface of the platform 19 and surrounding horizontal flanges 36 in superposed parallel relation thereto, these parts being permanently fastened together through rivets or bolts and nuts 37 passing through the surrounding flange portions 36, the body of the supporting platform 19 and angle reinforcing bars 38.

The fire pot 20' is preferably of cylindrical formation (Figure 4) and has the removable bottom 39 (Figure 2) secured in place by bolts 40 (Figure 1) fixed at one end to the outside of the fire pot wall and passing downwardly through outwardly projecting lugs 41 (Figure 4) to be engaged by winged threaded nuts 42 in firmly securing the bottom 39 in place, the free ends of the bolts 40 having complementary threads to permit this operation.

The hollow bottom 39 is of substantial height to enable an accumulation of the oil or fuel represented at 43 therein, and in the downwardly dished central portion 44 of the latter for initially setting the apparatus into heating operation, it being noted that through the dished or center of the hollow bottom the supply pipe or

nozzle 45 for the fuel is introduced, the latter receiving its supply from any convenient source, as through a pipe 46 intervening said nozzle and a metering valve 47, diagrammatically depicted (Figures 1 and 3), and another pipe or lead 48 running from a detachable coupling 49 in communication with the main source of supply, wherever located, and of any optional design not important herein.

- 10 The top part of the fire pot is narrowed or constricted as at 32, previously stated, and has an inturned surrounding flange or lip 50 to cause deflection of the incoming air through the apertures 31 and arising fuel or gases towards the center of the fire pot to cause better mixing and combustion of the ignited fuel as it passes further upwardly through a substantially elongated chimney or outlet flue 51, discharging at an elevated or high point in the heating chamber 28 which discharges at the lower portion of said chamber, as indicated at 52, into an exhaust pipe 53 coupled thereto, ultimately delivering to the outlet pipe or equivalent 54. By delivering the products of combustion at the elevated point in the heating chamber 28, benefit from the heat influence thereof will be disseminated throughout the entire area of the heating chamber because of the compelled travel of the products of combustion in the downward direction in the chamber 28 to the exit thereof at the outlet 52—53, in which course of travel any freed soot or other objectionable matter may fall and accumulate on the top 55 of the casing 26, surrounding the fire pot 20', to be conveniently wiped off or removed by removing the detachable top 56 of the heating chamber 28 either when the device is installed in the pit or well or after the apparatus has been removed therefrom, of course, the inner grill section 57 having been withdrawn 40 to permit the operation in either respect.

Thumb nuts and complementary screws 55a form a detachable connection between the top 55 and inwardly turned flanges of the casing 26 surrounding the fire pot whereby the fire pot and associated parts may be removed with said top 55 when the latter is unfastened, and the fuel supply line is disconnected from the nozzle 45.

- It has been customary to ignite the fuel in a furnace of this character by inserting a torch or igniter through the top of the fire box to near the available fuel or oil supply at the bottom of said fire pot, such devices consisting of a rod bearing a wad of absorbent material at its inner end and having an extension constituting a handle at the other end. However, such devices because of their being left in the fire pot, when not in service, are objectionable in that they become constantly subjected to the intense flame or heat and warp or twist out of shape so that they must be discarded and renewed, etc. The present improvement of this igniter feature of the invention is in having the absorbent material, as asbestos, at the lower end of a freely jointed shaft, the outer or handle end 58 thereof being connected to a relatively broad cap 59, with a depending flange 60 interfitting with an upturned flange 61, surrounding an opening 62 in the top 56 of the heating chamber, the cooperating flanges 60—61 on the top and cap being loosely fitted or spaced apart, to permit lateral movement of the cap whereby to always insure seating of the flanges to secure a two-ring or line contact between the flange and body of the top and cap. The cap or handle portion is adjustable to regulate the length of the flexible shaft

by means of a thread and nut adjustable attachment 63, and the handle portion 58 of the shaft may serve to suspend the lower portion or asbestos-carrying portion of the shaft so that the seating of the cap on the top 56 of the heating chamber may be assured. On the other hand the depending end 64 universally connected as at 65 with the handle portion 58 of the flexible shaft carrying the ignitable absorbent material 65 (Figure 2) may move laterally in any direction beyond the sides of the nozzle 45 if the latter should be in the way of the introduction of the igniter.

The course of the fresh air being heated through the medium of the heating chamber 28, and in its passage through the device, is determined by certain baffles or walls (in instances rectangular in contour) and the wood or other inflammable work of the flooring, in connection with which the device is used is protected by the disposition of the baffles with reference to each other, and to the heating chamber, and with reference to the grill sections broadly, as suggested hereinbefore. The specific construction of these elements will now be pointed out.

As already noted, 57 represents the inner or "hot" central portion of the grill. 66 represents the outer surrounding portion of the grill which I have styled the "cold" section of the grill. These sections are formed and related to obviate dangerous heat conditions from being transmitted from the apparatus to the floor or wood-work to which the apparatus is applied. The outer grill section carries the depending rectangular baffle or partition 67 riveted thereto as at 68, the same being of oblong cross-section conforming to the general shape of the apparatus. This outside grill section has a multitude of air inlet passages 69 and 70 passing therethrough, of a number and shape desired, whereby the cooler air of the room may pass therefrom downwardly through the flue 71 in the direction of the arrow (Figure 1), formed by the partition 67 and the outer casing 14 of the apparatus. The lower end of the partition or baffle 67 suspends freely from the grill section 66, being vertically slotted at its lower end 72 to slip over or be raised from the pipe section 53. The lower end of this baffle 67 terminates somewhat above the platform 19 that constitutes the major portion of the closure for the bottom of the apparatus. A like baffle or partition 73 is carried by and suspends from the hot grill section 57, being riveted thereto at 74 and arranged so that in assembled condition and operation this partition or baffle 73 is spaced from the first-mentioned baffle 67 to provide a supplemental air space or insulating area 75 between the baffles.

The baffle 73 is adapted to be slipped downwardly over the pipe section 53 in the same manner as already described in connection with the baffle 67. In other words these baffles are just alike save the diameters are different, permitting the nesting of the baffle 73 within the outer baffle 67. The operation will be understood when it is recalled that the cooler air entering the flue 71 will pass around the lower ends of the baffles 67 and 73 and upwardly through the continuation 76 of the said flue to, and in contact with, the sides and top of the heating chamber 28, whence the heated air will pass upwardly through the central grill section 57 to the room.

Referring to Figures 5 and 6 it will be observed that the outer grill section 66 has an outwardly extending circumferential main supporting flange 77 adapted to rest upon the floor of the structure in connection with which the heating apparatus

is employed, a downwardly extending flange 78 received in the floor opening, a downwardly directed flange 79 to accommodate the rivets 68, and an inwardly directed ledge 80, the upper surface of which, together with the adjoining vertical surface of the wall 81 of this grill section, forms a firm angular seat 82 to receive a complementary flange or lug 83 projecting outwardly from the edge of the grill section 57. This grill section 57 in turn carries the partition or baffle 73 riveted to the same at 74, as previously referred to. The inwardly directed supporting ledge 80 is of increased or heavy thickness where it joins the wall 81 of the grill to afford the adequate strength required, as clearly seen in Figure 6, and in order to give the central grill portion 57 a capability to withstand excessive weights and the like superimposed thereon, said section is of trussed formation, in other words downwardly increased in height to give the added metal and strength at the point most needed.

Two important advantages result from the provision of the sectional grill, one the ease and facility with which the central portion of the grill may be withdrawn, as desired, with suspended portions of the apparatus, the same being true of the outer grill section and its suspended parts, to open up the interior of the furnace and permit withdrawal of the fire pot, heating chamber, etc.; and to prevent excessive heat being conducted from the heating chamber directly through an integral grill furnace to the flooring or equivalent supporting structure.

In particularly describing the fragmentary sections or detail views, Figures 5 and 6, it is to be observed that but a single supporting ledge 80 and complementary superposed flange 83 was recited. However, as a matter of fact, the ledge and flange do not extend continuously around the grill but are a number of fittings of reduced extent, so far as possible, to afford enough supporting strength for the underlying structure while avoiding, so far as possible, continuous metal contact between the two grill sections. This leaves open spaces between the inner and outer sections of the grill for the passage of air from the space 79 between the baffles 67 and 73. Furthermore, even where the flanges or lugs 83 and ledges 80 are present it is desirable at times that their contacting surfaces may be minimized and heating radiation from the central section of the grill augmented by the presence of fins or ribs 85 on one of the members along the meeting rim between the same and the other of said members.

86 is a door hinged horizontally in a suitable cut-away portion of the grill section 57 to afford access to the igniter.

88 is a vertically slideable door in the nature of a panel, constituting the lower portion of one of the end walls of the outer casing of the apparatus affording access to the interior, if found necessary or desirable. This slideable door 88 works up-and-down in the ways or grooves 18 provided between the angle upright 16, 16a and the portions 14, the sliding door being adapted to be held in lifted position, at any point desired, by a spring catch 89 in the wall portion 14 adapted to frictionally engage or interlock with 70 a suitably formed part of the door.

A baffle 90 of L-formation depends from the baffle 73, being welded thereto at 91 to depend therefrom and be interposed between the metering valve 47 and the fire pot to protect the area around the metering valve as required by insur-

ance practices. The improvement in the instant supplemental baffle 90 is in the idea that the same is inserted in position with and supported from the baffle 73, and may be removed away from the metering valve to permit better access thereto.

To permit the platform 19, with all of the parts carried thereby, including the exhaust pipe 53, to be tilted and withdrawn from the outer casing, the connection between the said exhaust pipe 53 and the outlet pipe or flue 54 is such that the interior mechanism (pipe 53, heating chamber 28, platform 19, etc.) may be rocked or tilted in a vertical direction as well as moved to the right away from the outlet pipe 54. For this purpose the end of the exhaust pipe 53 is extended freely towards and into the flared or bell-shaped end 92 of the outlet pipe 54, and a close fitting or sealing ring 93 is sleeved upon the exhaust pipe 53 to be frictionally held, or otherwise fastened thereon, so that normally said ring 93 may be forced outwardly against the flared or bell-shaped end 92 of the outlet pipe to close the space between the two pipes 53 and 54, and on the other hand, as occasion requires, may be slid inwardly along the pipe 53 to permit a tilting of the latter in the end of the pipe 54 to permit the platform 19 and parts thereon to be correspondingly tilted upwardly to free the engagement between the same and its inverted U-shaped bar or supporting member 20 when the whole of this interior construction, now under consideration, may be moved to the right and the exhaust pipe 53 sufficiently shifted away from the outlet pipe 54 to permit vertical raising of the interior structure within the outer casing.

It will be noted that the contacting face of the ring 93, with the bell-shaped end 92, is of the same curve configuration as at 94 to afford a broad surface contact.

I claim:

1. In a floor furnace, an outer casing adapted for installation in a pit and having means provided at the bottom thereof for the passage of air from the atmosphere into the interior of said casing, a spring flange carried by said outer casing horizontally around its inner surface at a level above said air-inlet means, a base plate adapted to rest upon and resiliently engage said spring flange, an inner casing affixed to the upper side of said base plate forming a heating chamber, a fire pot mounted within said heating chamber,

means permitting flow of air from said air-inlet means to the interior of said fire pot, a stack carried by said fire pot operative to discharge the products of combustion into the heating chamber at the upper portion thereof, a main exhaust pipe affixed to the outer casing, and means affixed to the inner casing connecting the lower portion of the heating chamber with said main exhaust pipe.

2. In a floor furnace, an outer casing adapted for installation in a pit and having means provided at the bottom thereof for the passage of air from the atmosphere into the interior of said casing, a spring flange carried by said outer casing horizontally around its inner surface at a level above said air-inlet means, a base plate adapted to rest upon and resiliently engage said spring flange, an inner casing affixed to the upper side of said base plate forming a heating chamber, a fire pot mounted within said heating chamber, means permitting flow of air from said air-inlet means to the interior of said fire pot, a stack carried by said fire pot operative to discharge the products of combustion into the heating chamber at the upper portion thereof, a main exhaust pipe affixed to the outer casing, an inner exhaust pipe affixed to the inner casing near the lower end thereof and adapted to register at its outlet end with the inlet end of said main exhaust pipe, and a resilient bushing slidably mounted on the inner exhaust pipe adapted to form a gas-tight seal between the two exhaust pipes when they are in registering position.
